(57) **CLAIM**

The ornamental design for a part of a tool adaptor, as shown and described.

DESCRIPTION

FIG. 1 is one perspective view of the first embodiment of a part of a tool adaptor showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view of the second embodiment of the part of a tool adaptor; and,

FIG. 9 is another left side view thereof.

Wherein the broken line portions of FIGS. 1-5 and 7 show the first embodiment of a connecting member of the tool adaptor; and the broken line portions of FIGS. 8-9 show the second embodiment of the connecting member of the tool adaptor. The broken lines in the drawings are for the purpose of illustrating portions of a part of a tool adaptor which form no part of the claimed design.
